CLAIM

The ornamental design for a mouse, as shown and described.

DESCRIPTION

FIG. 1 is a front elevational view of the mouse showing our new design;

FIG. 2 is a top plan view thereof;

FIG. 3 is a bottom plan view thereof;

FIG. 4 is a right side elevational view thereof;

FIG. 5 a left side elevational view thereof; and,

FIG. 6 is a cross-section view taken along line A—A of FIG. 5 omitting the inside mechanism thereof.

The rear elevational view of the mouse is a mirror image of the front elevational view of FIG. 1.
